UNITED STATES PATENT OFFICE

WILLIAM F. MINNICK, OF NILES, OHIO, ASSIGNOR TO THE HARRIS AUTOMATIC PRESS COMPANY, OF NILES, OHIO, A CORPORATION OF OHIO.

SHEET FEED OR SEPARATOR.

1,110,704.

Specification of Letters Patent. Patented Sept. 15, 1914.

Application filed June 27, 1913. Serial No. 776,166.

To all whom it may concern.:

Be it known that I, WILLIAM F. MINNICK, of Niles, in the county of Trumbull and State of Ohio, have invented certain new and useful Improvements in Sheet Feeds or Separators; and I do hereby declare the following to be a full, clear, and exact description of the invention, such as will enable others skilled in the art to which it appertains to make and use the same.

This invention relates to sheet-feeds or separators, and is especially designed for handling glazed or coated material and also comparatively thick stock, such as cardboard or pasteboard.

In the accompanying drawings, Figure 1 is an elevation showing a portion of a feeder equipped with my improvements. Fig. 2 is a view in perspective of a portion of the separator. Fig. 3 is a plan view thereof. Fig. 4 is a section on line 4—4 Fig. 3.

The distinguishing characteristic of my present invention resides in effecting the buckling of sheets from opposite corners toward each other by reciprocating means designed to engage the edges of the sheets and to be moved inwardly over the pile sufficiently to buckle the topmost sheet so that it may be removed by any preferred means.

In the drawings I have shown my invention applied to a feeder of the type disclosed in the application for patent of Charles G. Harris, filed February 19, 1910, Serial No. 544,753, and my improvements may readily be applied to the Harris feeder without involving any material change in construction. The parts are duplicated at each side of a pile of stock and the description of one series of elements will apply to both.

I have shown a vertically-movable suction-separator 1 carried by an arm 2; an air ejecting presser-foot 3 carried by an arm 4; and a buckler 5 which is controlled by an arm 6, all of which arms are engaged by suitable cams mounted on a common operating shaft which may be driven by any suitable agency. It is not necessary to refer in detail to the construction of either the suction-separator or the presser-foot and blower.

The buckler 5 is in effect a pusher. It rests upon a pile of stock, near its edge, and is provided on its under surface with a protruding edge or projection 7 which is de-

signed to engage the edge of the stock. It is only necessary that the buckler be reciprocated inwardly, transversely of the pile, sufficiently to buckle the top sheet, and when the latter is taken up by the separator the buckler is returned to its starting point, being moved sufficiently far to enable its edge or projection 7 to clear and engage the edge of the top sheet. The particular formation of the buckler is immaterial. In general, it is substantially the pusher of patent to John F. McNutt, No. 605,328, of June 7, 1898, with the difference in construction that the projection is on the underside instead of on top as shown in said patent, and the difference in function that in the present instance the device is used solely to buckle the topmost sheet by engaging the opposite edges thereof, but not to feed it from the pile. The degree to which the edge or projection extends beyond the undersurface of the buckler may be controlled by adjusting screws 8. The buckler has a limited rotary movement on a stud 9 which is pivotally mounted on the lower end of an outwardly projecting arm of a lever 10. A post 12 of the stud is connected by a spring 13 to a post 14 extending outwardly from the lever, said spring tending to always hold the buckler under sufficient tension against the top of the pile.

The lever 10 is fulcrumed at 15 on the front face of a vertically-disposed plate 16 secured to a frame 17 which carries the several units composing the separating device. The lever 10 has a slot 18 extending longitudinally therein but at a slight angle to the axis of the lever, and into this slot projects the end of a rod or shaft 19 which is also projected through a straight slot 20 in the supporting plate 16. The rod or shaft 19 is carried by the arm 6. I have shown this rod or shaft as mounted in a bearing 21 pivoted concentrically to the operating shaft 22 on which the several cams are located, and as having a friction roller 25. The bearing 21 is connected to the arm 6 by means of a rod 26 so that as said arm is raised by its respective cam 27 the rod or shaft 19 will move upwardly in the slots of the lever 10 and the plate 16, and by reason of the pitch of the slot in the lever will cause the latter to move outwardly and carry the buckler with it. As the cut-out or depression 28 of cam 27 is

brought beneath the friction roller 29 of arm 6 the latter will be immediately lowered, causing the quick descent of the rod or shaft 19, and the consequent quick inward movement of lever 10 and with it the buckler. To insure the quick downward movement of arm 6 I preferably connect to rod 26 a spring 30 which is placed under tension when said arm 6 is raised, and to further aid in effecting this movement I may also use a second spring 31 connected to arm 6 at a point near its pivot.

Assuming that the pile support has been properly adjusted, and that the bucklers bear with sufficient pressure on the top of the pile, in each operation the bucklers when moved inwardly by the lowering of the actuating rod or shaft 19 will through the projecting edges on their under surfaces engage the opposite edges of the topmost sheet at opposite sides of the pile, and being moved inwardly will effect the necessary buckling to permit such sheet to be taken up by the separator and removed from the pile by any suitable means, not shown. In this connection it will be understood that the presser-foot is raised from the pile and moved outwardly and then forwardly to eject air beneath the topmost sheet and to re-engage the pile. On the return movements of the actuating rods of shafts 19, effected by the raising of their carrying arms 6, the bucklers will be moved outwardly to permit the edges or projections 7 to clear the edges of the pile and be in position to engage the topmost member thereof when again moved inwardly.

The advantages of the present invention will readily be appreciated by those skilled in the art. By means of my present improvement the positive separation of the sheets is effected, and all danger of marking the stock is avoided. This is of particular importance in handling certain kinds of coated paper the appearance of which is likely to be impaired where separation depends upon a positive frictional contact with the surface of the stock.

I claim as my invention:

1. In a sheet feed or separator, means for forming buckles in the topmost sheet of a pile of stock, comprising two oppositely disposed bucklers adapted to rest on top of the pile at the extreme edges thereof and having on their undersides projections extending below the plane of the top surface of the topmost sheet for engaging opposite side edges thereof at right angles to said top, and means for simultaneously moving said bucklers toward each other to cause said projections to positively engage said side edges of the topmost sheet to produce buckles therein.

2. In a sheet feed or separator, means for forming buckles in the topmost sheet of a pile of stock, comprising two oppositely dis-

posed bucklers adapted to rest on top of the pile at the extreme edges thereof and having on their undersides projections extending below the plane of the top surface of the topmost sheet for engaging opposite side edges thereof at right angles to said top, and means for simultaneously moving said bucklers toward each other, said bucklers constantly resting on the top of the pile and said projections positively engaging said side edges of the topmost sheet as the bucklers are moved toward each other to buckle the sheet.

3. In a sheet feed or separator, in combination, a buckler designed to rest on the top of a pile of stock and having means for engaging the edge of the topmost sheet of such pile at right angles to the top of the pile, a carrier for said buckler, and means engaging said carrier for moving it inwardly and outwardly relatively to the edge of the pile while the buckler remains in constant engagement with the latter.

4. In a sheet feed or separator, in combination, a buckler designed to be reciprocated relatively to the edge of a pile of stock and having means for engaging the edge of the topmost sheet of such pile at right angles to the top of the pile, a carrier for said buckler, means engaging said carrier for moving it inwardly and outwardly relatively to the edge of the pile, and means acting on the last mentioned means for imparting a relatively quick movement thereto in moving the buckler inwardly to engage the stock.

5. In a sheet feed or separator, in combination, a buckler designed to be moved relatively to the edge of a pile and having means for engaging the edge of the topmost sheet of the pile, a carrier for said buckler, said carrier having a diagonally positioned slot, and a reciprocating member movable on a straight line and extended into said slot for shifting said carrier.

6. In a sheet feed or separator, in combination, a buckler designed to be moved relatively to the edge of a pile and having means for engaging the edge of the topmost sheet of the pile, a carrier for said buckler, said carrier having a diagonally positioned slot, a rod or shaft extending into said slot and movable on a straight line, and means for actuating said rod or shaft to effect the shifting of said carrier.

7. In a sheet feed or separator, in combination, a buckler designed to be moved relatively to the edge of a pile and having means for engaging the edge of the topmost sheet of the pile, a carrier for said buckler, said carrier having a diagonally positioned slot, a support for said carrier having a straight slot, a rod or shaft extended through both of said slots, and means for moving said rod or shaft in opposite direc-

tions to reciprocate said buckler and its carrier.

8. In a sheet feed or separator, in combination, a buckler designed to rest on the top of the pile of stock and having a projection for engaging the edge of the topmost sheet of the pile, a carrier for said buckler, a reciprocating element for shifting said carrier, a pivoted arm supporting said ele-
10 ment, a cam for moving said arm, and spring

mechanism for moving said arm independently of said cam.

In witness whereof, I have signed this specification in the presence of two subscribing witnesses.

WILLIAM F. MINNICK.
